(57) **CLAIM**

The ornamental design for a leveling lift block, as shown and described.

DESCRIPTION

FIG. 1 is a top perspective view of a levelling lift block, showing my new design;

FIG. 2 is a bottom perspective view thereof;

FIG. 3 is a front elevational view thereof, the rear elevational view is identical;

FIG. 4 is a left side view thereof;

FIG. 5 is a right side view thereof;

FIG. 6 is a top view thereof; and,

FIG. 7 is a bottom view thereof.

The broken lines in the drawings depict portions of the levelling lift block that form no part of the claimed design.
